RELAY MOUNTING

James E. Russo, Locust, N.J., assignor to Wheelock
Signals, Inc., Long Branch, N.J., a corporation of
New Jersey

Filed Aug. 9, 1963, Ser. No. 76,167

Term of patent 14 years

(Cl. D26—13)

FIG. 1.

FIG. 2.

FIG. 3.

FIG. 4.

FIG. 5.

FIG. 6.

FIG. 7.

FIG. 8.

FIG. 9.

FIG. 1 is a top plan view of one form of my new design for a one-piece relay mounting which shows a tunneled spool-like housing and integrally formed legs at both ends;

FIG. 2 is a side elevational view of the relay mounting shown in FIG. 1, the opposite side being substantially a mirror image thereof;

FIG. 3 is an end elevational view of the relay mounting shown in FIG. 1, the opposite end being substantially a mirror image thereof;

FIG. 4 is a bottom plan view of the relay mounting shown in FIG. 1;

FIG. 5 is a top plan view of another form of my new design for a relay mounting which shows the tunneled spool-like housing having a plurality of spaced-apart longitudinal slots therein;

FIG. 6 is a side elevational view of the relay mounting shown in FIG. 5, the opposite side being substantially a mirror image thereof;

FIG. 7 is an end elevational view of the relay mounting shown in FIG. 5, the opposite end being substantially a mirror image thereof;

FIG. 8 is a bottom plan view of the relay mounting in FIG. 5; and

FIG. 9 is a cross-sectional view of the relay mounting shown in FIG. 5 taken on line 9-9 in FIG. 5.

The relay mounting design is characterized by a tunneled spool-like relay housing having integrally formed slotted feet at both ends thereof. In the embodiment shown in FIGURES 1 through 4, the spool-like portion of the housing is formed by a continuous surface, whereas in the embodiment shown in FIGURES 5 through 9 the spool-like portion of the housing has a plurality of spaced-apart longitudinal slots therein.

I claim:

The ornamental design for a relay mounting, as shown and described.
